(57) **CLAIM**

The ornamental design for a cap for a bottle, as shown and described.

DESCRIPTION

FIG. 1 is a perspective view of a cap for a bottle in which the cap is transparent with a nontransparent inner portion;

FIG. 2 is a front view of thereof, with a rear view being a mirror image of the front view;

FIG. 3 is a right side view thereof, with a left side view being a mirror image of the right side view;

FIG. 4 is a top view thereof;

FIG. 5 is a bottom view thereof; and,

FIG. 6 is a cross-sectional view thereof taken along section lines 6—6 of FIG. 4.

The broken lines showing of the inside of the cap form no part of the claimed design.
